UNITED STATES PATENT OFFICE.

CHARLES H. GUNN, OF OAKLAND, CALIFORNIA.

SEAT-CONTROLLED TOILET FLUSH AND INTAKE VALVE.

Application filed June 16, 1924. Serial No. 720,211.

To all whom it may concern:

Be it known that I, CHARLES H. GUNN, a citizen of the United States, residing at Oakland, county of Alameda, State of California, have invented certain new and useful Improvements in Seat-Controlled Toilet Flush and Intake Valves; and I do declare the following to be a full, clear, and exact description of the same, reference being had to the accompanying drawings, and to the characters of reference had thereon, which form a part of this application.

This invention relates to improvements in flush and intake valve structures for toilets, my principal object being to provide intake and flush or discharge valve means, usable in connection with an airtight pressure tank, which valve means will be actuated in common but alternately, by the user of the toilet, in such a manner that while water is entering the tank through the intake, no water can pass out through the flush pipe, and vice versa. This insures that the same quantity of water, and no more, will always be used for flushing purposes, and prevents waste of water.

Another object is to provide a control means for the valve structure so arranged that the tank will automatically fill up only when a person is seated on the toilet, and will also automatically empty or flush whenever said person rises from the seat. This insures that a flushing action will be had irrespective of any thoughtfulness, or lack of the same on the part of the user, since the valves are actuated without any conscious effort of the user being necessary.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a side view of the complete structure as installed in connection with a toilet bowl.

Fig. 2 is a top plan view of the same.

Fig. 3 is a side section of the valve structure.

Fig. 4 is a vertical section on the line 4—4 of Fig. 3.

Fig. 5 is a sectional plan on the line 5—5 of Fig. 3.

Fig. 6 is a fragmentary top plan view of the valve.

Referring now more particularly to the characters of reference on the drawings, the numeral 1 denotes a toilet bowl of ordinary character, hinged to the rear end of which is the seat 2. Disposed back of and above the bowl and secured to a wall 3 is an airtight tank 4 of suitable design and size.

My improved valve structure, operable with these elements, comprises a casing 5 threaded at its upper end to screw into the bottom of the tank, and being covered at said end by a wall 6 except for a centrally located tapered valve-seat opening 7.

The lower end of the casing is adapted for connection to a flush-L 8 leading to the bowl 1 at the customary place.

A water intake pipe 9 is connected to the casing on one side thereof, and communicates with a passage 10 formed in the casing and leading to the upper end of the same. The upper end of this passage communicates with a pipe 11 which is disposed between the wall 6 and a crosshead member 12 above said wall and extending diametrically of the casing. This crosshead has a passage 13 leading from the pipe 11 to the lower face of the head in vertical alignment with the opening 7.

A plunger 14 is mounted within the casing, being vertically slideable and guided by suitable means 15 in the casing, the plunger being positioned in concentric alignment with the opening 7 and lower termination of the passage 13. A valve head 16 is mounted on top of the plunger. The sides of this head are tapered to fit in the opening 7, while the upper face thereof is recessed to receive a valve seat member 17 of rubber or the like adapted to make contact with the under face of the member 12 and to then close the passage 13. The head 16 is of such a thickness that a certain amount of vertical movement of the plunger will be had between the closing of the passage 13 and the opening 7. The valve head is normally held in its uppermost position by a compression spring 18 seated on the crosshead 12. A strap or bar 19 extends over and rests on top of the

spring, to which strip are connected rods 20 which extend down alongside the crosshead and are attached at their lower ends to the valve head 16. It will thus be seen that a 5 constant and direct pressure is applied to the valve head to hold the same against the water intake passage 13, the spring being of a strength sufficient to overcome the pressure of the water tending to force the valve 10 down.

To enable the member 17 to be removed and renewed when necessary without disconnecting the casing from the tank, the tank in front of and in horizontal alinement with 15 the valve head is provided with a detachable plug 21 of sufficient size to permit of the insertion of a tool to pry up and remove the member 17. A short length of pipe 22, tipped with a rubber bumper 23, is preferably mounted with said plug to serve as a 20 stop for the seat 2 when the latter is raised and prevent contact of said seat with the tank.

To lower the plunger and valve head from 25 engagement with the intake opening to a seat in the discharge-opening 7, I provide a horizontal arm 24 fixed in the casing 5 on a shaft 25 extending at right angles to the plane of the plunger, the free end of said 30 arm extending into a slot 26 provided in the plunger.

The outer end of said shaft, outwardly of 35 the casing, has an arm 27 thereon extending in the opposite direction to the arm 24. On the outer end of arm 27 is an adjustment screw 28, vertically disposed, which is 40 adapted to abut against the free end of a stiff, flat spring 29 rigidly fixed on and projecting rearwardly of the seat 2, said seat and spring forming a lever the fulcrum of which is the hinge pin 30 of the seat.

This spring is so disposed that when the 45 seat is abutted against the bowl, the arm 27 is raised and the arm 24 lowered a sufficient distance to cause the valve 16 to seat in the orifice 7. By reason of the member 29 being a spring rather than an unyieldable piece, no undue and possibly disastrous strain is placed on any part in the event that 50 the valve should firmly seat in the discharge opening before the seat is fully lowered.

The seat is normally held raised a certain 55 distance, so as to cause the spring 29 to be free of the arm 27 and enable the spring 18 to act on and draw the plunger to its upward limit of travel, by suitable spring means between the seat and the bowl, as shown at 31. The resistance of this spring is of course overcome when a person occupies the seat.

60 To insure that when installing these devices, the bowl will always be the same distance from the valve structure, I provide a plate 32 adapted to be secured at one end to the bowl in common with the seat hinges, and at its other end to fit over the lower end

of the casing 5 above the flush-L connection.

In operation, the tank is empty when the seat is in its normal semi-raised position, since the flush opening 7 is then unobstructed as previously set forth. As soon as the 70 seat is lowered by the weight of a person thereon, the flush opening is closed and the intake passage opened, allowing the tank to fill. Although the person may occupy the seat for a longer time than is necessary 75 for the tank to become full, this will do no harm, since the tank being an airtight pressure structure, when filled it cannot overflow, and the pressure of the water in the tank and in the intake pipe will merely be 80 come equal.

As soon as the downward pressure is removed from the seat, the latter is forced upward by the spring 31, causing the flush opening 7 to be opened and the intake passage 13 closed, by reason of the mechanism already described. The bowl will therefore be flushed until the tank is empty, when no more water will enter the same until the 90 seat is again depressed.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended 100 claims.

Having thus described my invention what I claim as new and useful and desire to secure by Letters Patent is:

1. A combined toilet-tank intake and flush valve comprising a casing, an orificed wall across the upper end thereof, said upper end being adapted for direct connection to a tank whereby the orifice will open into the latter, a discharge outlet at the lower end of the casing, intake passage means extending inside the casing from one side thereof below the tank to a point above the end wall and facing the orifice therein, and a closure member interposed between said orifice and the adjacent end of the intake passage.

2. A combined toilet-tank intake and flush valve comprising a casing, an orificed wall across the upper end thereof, said upper end being adapted for direct connection to a tank whereby the orifice will open into the latter, a discharge outlet at the lower end of the casing, an intake passage terminating above and facing said orifice, a common closure member interposed between said orifice and adjacent end of the intake passage, and means for operating the closure member from one side of the casing whereby to permit the discharge outlet be- 125 130

ing in vertical alinement with the upper end orifice to permit of a straight and unobstructed flow of water through the casing from the tank being had when the orifice closure is moved from the same.

3. A combined toilet intake and flush valve comprising a casing, an orificed wall across the casing at one end and a discharge outlet at the opposite end, a crosshead 10 mounted on and outside the casing in spaced relation to the wall, intake passage means leading from one side of the casing into said crosshead and terminating in an opening facing the wall opening, a valve member movable between said openings to alternately close the same, rods attached to said member and projecting past the crosshead, a connection between the outer ends of said rods, and a spring between said connection 15 and the crosshead.

4. A combined toilet intake and flush valve comprising a casing, an orificed wall across the casing at one end and a discharge outlet at the opposite end, a crosshead 20 mounted on and outside the casing in spaced relation to the wall, intake passage means leading from one side of the casing into said crosshead and terminating in an open- 25

ing facing the wall opening, a valve member movable between said openings to alternately close the same, spring means mounted beyond the crosshead and operatively connected to the valve member to cause the same to normally close the intake opening, and means applied to the valve member inside the casing for moving said member in the opposite direction at will.

5. A combined toilet intake and flush valve comprising a casing, adapted at its upper and lower ends for direct connection to the 30 bottom of a tank and a flush pipe respectively, a wall across the top of the casing, having an orifice in line with the lower end opening of the casing, intake passage means provided as a unit with the casing and leading up inside the same from a point intermediate its ends to a termination in an opening above and facing the wall orifice, a common closure means for said intake and 35 wall openings positioned therebetween, and control means for said closure means mounted in the side of the casing below the upper end thereof and operatively connected to the closure means.

In testimony whereof I affix my signature.
CHARLES H. GUNN.
